UNITED STATES PATENT OFFICE

141,925

DESIGN FOR A TOY DREDGE

Eoina Nudelman, Chicago, Ill.

Application March 10, 1945, Serial No. 118,386

Term of patent 3½ years

(Cl. D34—15)

To all whom it may concern:

Be it known that I, Eoina Nudelman, a citizen of France, residing at Chicago, in the county of Cook and State of Illinois, have invented a new, original, and ornamental Design for Toy Dredges, of which the following is a specification, reference being had to the accompanying drawing, forming part thereof.

Fig. 1 is a side elevational view of a toy dredge, showing my new design;

Fig. 2 is a top plan view;
Fig. 3 is a rear view; and
Fig. 4 is a front elevational view of the right-hand lower portion of Fig. 1.

I claim:

The ornamental design for a toy dredge, as shown.

EOINA NUDELMAN.
